HOUSE MODEL

Frank Bolhuis, Holland, Mich.

Application February 25, 1939, Serial No. 258,421

5 Claims. (Cl. 35—16)

The present invention relates to house models, and more particularly to structures adapted for use by architects, contractors, or lumber companies for demonstration and selling purposes.

This application is a continuation in part of my copending application Serial No. 190,385, filed February 14, 1938; and also relates generally to the subject matter of my Patent No. 2,118,338, issued May 24, 1938.

10 The primary objects of the present invention are to provide such a house model having an improved frame for the reception and retention of interchangeable floor plan panels and wall panels, said frame being extensible in length 15 and breadth; to provide improved frame elements which are so constructed that they are readily adaptable for assembly into a rectangular frame or into a frame of irregular configuration depending upon the character of the 20 house to be portrayed; to provide improved means whereby realistic representations of windows and doors may be provided in the wall panels; and, to provide such a structure whose constituent parts are of simple and economical 25 construction and of especial adaptability for their intended use.

An illustrative embodiment of the invention is shown in the accompanying drawings, wherein:

Figure 1 is a perspective view of a house model, 30 the particular model there illustrated being of extremely simple design and being but one example from a great variety of such models which might be built upon the same frame;

Figure 2 is a perspective view of the house model illustrated in Figure 1, the roof and certain wall panels being omitted to disclose the skeleton frame of the structure;

Figure 3 is an enlarged side elevational view of a corner portion of the skeleton frame per se;

Figure 4 is a top plan view thereof and showing wall panels associated therewith;

Figure 5 is a sectional view on line 5—5 of Figure 3;

Figure 6 is a top plan view similar to Figure 4 but showing a recessed corner;

Figure 7 is a side elevational view of a corner portion of a two-story skeleton frame;

Figure 8 is an enlarged sectional view on lines 8—8 of Figures 1 and 9; and

Figure 9 is an enlarged sectional view on lines 9—9 of Figures 1 and 8.

Referring then to these drawings in which like numerals designate like parts in the several views, the house model illustrated in Figures 1 and 2 comprises a skeleton frame generally

designated 10, a floor plan panel 11, a front wall panel 12, a rear wall panel 13, and end wall panels 14 having upwardly inwardly tapered portions 15 supporting a removable roof 16. As shown in Figure 1, the front wall panel 12 is 5 provided with a portal 17 secured thereto in any suitable manner as by glue or brads, and a gable 18 is removably disposed on the portal 17 and roof 16.

The skeleton frame 10 is supported at the corners thereof by vertically disposed corner posts 19 each of which comprises a pair of corner rails 20 having medial portions 21 secured together as by spot welding. Parallel flanged portions 22 of each corner rail 20 form a longitudinal panel 15 receiving slot 23 therebetween, the oppositely disposed slots of adjacent corner posts 19 being adapted to receive and retain the opposite ends of a wall panel 12, 13 or 14 bearing thereon a representation of the wall of a house. 20

Frame corner members 24 comprise web portions and outer side flanges 25 which laterally depend from said web portions and which are secured as by spot welding to the angularly meeting inner surfaces of the corner posts 19 25 adjacent the upper and lower ends of these posts 19. The several lower corner members 24 form a support for the floor panel 11 removably disposed thereupon and bearing on its upper surface the floor plan of a house. 30

The frame corner members 24 are each further provided with a pair of inner side flanges 26 laterally depending from the web portions and whose inner side surfaces are disposed at right angles to each other, and a sleeve 27 projects laterally from each flange 26 and is secured thereto as by passing the reduced end portion 28 of the sleeve through an aperture in the flange and riveting over the extreme end of the sleeve. 35

Rods 29 forming the side rails of the skeleton frame have their opposite ends slidably fitted in the sleeves 27 of the frame corner members 24 secured to adjacent corner posts 19, and set screws 30 threaded in the sleeves 27 provide means for securing the rods in adjusted positions relative to the sleeves. By this arrangement the skeleton frame is rendered extensible in length and breadth to accommodate floor plan panels of different sizes and shapes and wall panels of 50 different widths.

Figure 6 illustrates the manner in which a recessed corner may be built into the structure. A bent rod 29¹ is here shown connecting the adjacent sleeves 27 of similarly disposed frame cor- 55

ner members 24, and a wall panel 31 is received and retained in the slots of corner posts 19 and comprises two sections 32 and 33 secured together at right angles as by brads 34.

- 5 It will readily be seen that by the use of rods 29 of different lengths and rods 29¹ likewise of different lengths and bent at any desired angles, the structure is adaptable for portraying houses of virtually any configuration.
- 10 In portraying a two story structure, longer corner posts 19¹ are employed as illustrated in Figure 7, and the wall panels used bear representations of the walls of a two story structure. If desired, frame corner members 24¹ having 15 outer side flanges 25¹ and inner side flanges 26¹ of identical construction as the frame corner members 24, may be secured to the corner posts 19¹ intermediate the ends thereof, and a second floor plan panel 11¹ may be removably disposed 20 on and supported by said corner members 24¹. It will further be seen that the number of stories in the structure may be increased by using still longer corner posts, appropriate wall panels, and a greater number of floor plan panels and supporting frame corner members therefor.

Figures 1, 8 and 9 illustrate improved means for realistically representing windows in the various wall panels. A preferably stamped sheet metal frame generally designated 34a comprises a sill 30 portion 35, side casing portions 36, a head casing portion 37, side jamb portions 38 having vertical grooves 39 therein for the reception of a glass plate 40 bearing thereon a painted or otherwise applied representation of a divided window, and 35 springable side flanges 41 adapted to bear against the sides 42 of a rectangular opening 43 in a wall panel 12 to thus removably secure the frame within said opening. Similar frames are provided for the door openings which extend to the floor 40 panels, the plates 40 in such door frames bearing the representation of a door.

It will be seen that the representations of windows and doors in the selected wall panels conform to the indications of windows and doors on the selected floor plan, so that upon removal of the roof 16, prospective builders may readily form a mental picture of the interior of a proposed house simulated by the house model.

It will further be seen that the various parts 50 of the structure may be interchanged, rearranged, substituted for by similar parts, or added to with similar parts to form a great variety of house models to aid prospective builders in the selection of a home. Moreover, the various parts are ruggedly and reasonably economically constructed, 55 may be conveniently assembled, and are particularly well adapted for their intended use.

While but several specific embodiments of the invention have been herein shown and described,

it will be understood that certain details of the constructions shown may be altered or omitted without departing from the spirit of this invention as the same is defined by the following claims.

5 I claim:

1. In a skeleton frame for a structure of the class described comprising a plurality of angularly disposed side rails, a frame corner member having a horizontal web portion and a pair of inner side flanges depending from said web portion and disposed at an angle to each other, and means secured to and projecting laterally from each inner side flange adapted to slidably embrace a side rail of the skeleton frame. 15

2. In a skeleton frame for a structure of the class described comprising a plurality of angularly disposed side rails, a frame corner member having a horizontal web portion and a pair of inner side flanges depending from said web portion 20 and disposed at right angles to each other, and means secured to and projecting laterally from each inner side flange adapted to slidably embrace a side rail of the skeleton frame.

3. In a skeleton frame for a structure of the class described comprising a plurality of angularly disposed side rails, a frame corner member having a horizontal web portion and a pair of inner side flanges depending from said web portion 25 and disposed at an angle to each other, and a sleeve secured to and projecting laterally from each inner side flange adapted to slidably embrace a rod forming a side rail of the skeleton frame. 30

4. In a skeleton frame for a structure of the class described comprising a plurality of angularly disposed side rails, a frame corner member having a horizontal web portion and a pair of inner side flanges depending from said web portion and disposed at an angle to each other, a 35 sleeve secured to and projecting laterally from each inner side flange adapted to slidably embrace a rod forming a side rail of the skeleton frame, and a set screw threaded in each sleeve and adapted to secure the rod in adjusted position relative to the sleeve. 40

5. In a skeleton frame for a structure of the class described comprising a plurality of angularly disposed side rails, a vertically disposed corner post having angularly disposed inner surfaces, a plurality of vertically spaced frame corner members each having a horizontal web portion and a pair of outer side flanges depending from said web portion and secured to the inner surfaces respectively of said corner post, and 55 means secured to some of said frame corner members adapted to slidably embrace a side rail of the skeleton frame. 50

FRANK BOLHUIS.
